(57) **CLAIM**

The ornamental design for a solar floating fountain, as shown and described.

DESCRIPTION

FIG. 1 is front, right, and top perspective view of a solar floating fountain with the bottom features in an extended state, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is another front, right and top perspective view of the solar floating fountain with the bottom features in a retracted state; and,

FIG. 12 is another rear, left and bottom perspective view of the solar floating fountain of FIG. 11.

The broken lines depict portions of the solar floating fountain that form no part of the claimed design. The dot-dash broken lines in FIGS. 1, 2, 9, and 10 depict the boundaries of the enlargements that form no part of the claimed design.

1 Claim, 12 Drawing Sheets
